UNITED STATES PATENT OFFICE.

WILLIAM S. CALLERY AND ROY SETTLE, OF ST. JOSEPH, MISSOURI.

LEGGING.

SPECIFICATION forming part of Letters Patent No. 765,065, dated July 12, 1904.

Application filed October 20, 1903. Serial No. 177,736. (No model.)

To all whom it may concern.:

Be it known that we, WILLIAM S. CALLERY and ROY SETTLE, citizens of the United States, residing at St. Joseph, in the county of Buchanan and State of Missouri, have invented certain new and useful Improvements in Leggings; and we do hereby declare the following to be a full, clear, and exact description of the invention, such as will enable others skilled in the art to which it appertains to make and use the same, reference being had to the accompanying drawings, and to the letters of reference marked thereon, which form a part of this specification.

15 Our invention relates to that class of leggings intended to reach down to and cover the entire foot; and in our improved legging we extend and hold the lower edge of the same, by the improved means hereinafter described, 20 over the edge of the sole of the boot or shoe instead of at the sole where it joins the upper, our object being, first, to exclude the water from entering the boot or shoe at the crevice where the upper is attached to the sole, and, 25 second, to provide an inexpensive means for holding the legging securely in said position.

In the accompanying drawings, Figure 1 is a side view of the legging as it appears upon the boot or shoe, the corner of the legging 30 carrying the strap-buckle being thrown back to permit a view of the sole of the boot or shoe. Fig. 2 is a perspective of the legging as it appears when strapped on the foot, showing by dotted lines the toe-piece fastened inside the legging and with which the stirrup has connection; and Fig. 3 is a cross-section of the 35 legging and with which the stirrup has connection; and Fig. 3 is a cross-section of the toe-piece and the legging broken away and a longitudinal section of the stirrup, its ends forming connection with said toe-piece.

40 Similar letters indicate similar parts in the different views.

The body of the legging A is made of any suitable material, and we ordinarily use hooks b b and eyelets c c, as shown, in connection 45 with a lacing d, for fastening; but we do not confine ourselves to this particular mode of attaching the same. Strips of canvas are inserted vertically inside the legging from top to bottom to strengthen the hold of said hooks

and eyelets, as shown by dotted lines in Fig. 50

1. Inside the toe of the legging we insert a bowed strip E, of pliable metal or other suitable material, fastening the same securely therein by rivets e e or in any convenient manner. Said strip E extends backward to about 55 the line of the ball of the foot. It is adapted to set solidly against the edge of the sole B of the boot or shoe to extend upward above the crevice where the upper of the boot or shoe connects with the sole and downward to a line horizontal 60 with the bottom of the sole, thereby preventing absolutely the entrance of water through the crevice formed between the top of the sole and the connection of the upper therewith. A stirrup H, adapted to support the foot and 65 draw the toe part of the legging and strip E down taut, is fastened at end h to said strip E at a line forward of the ball of the foot, the opposite end h' of said stirrup being inserted between the legging material and said strip 70 and bent downwardly inside the same, as shown in Fig. 3. The material of the stirrup being pliable, its end h' can be readily withdrawn from connection with strip E or lengthened or shortened, and it being thus adjust- 75 able a legging can be fitted and adapted to boots or shoes having soles of different widths or thicknesses or to those of any size. It will be understood that the particular manner of attaching said stirrup is immaterial, the essen- 80 tial feature being that it shall be made adjustable, thus adapting it to boots or shoes having soles either light or heavy. The part of the legging backward of said strip E is drawn down over the edge of the sole and held there 85 securely by means of strap K and buckle K' or in any similar way.

What we claim, and desire to secure by Letters Patent, is—

1. The combination of a legging, a bowed 90 pliable toe-piece attached at the bottom of the legging adapted to set against the edge of the sole of the boot or shoe at the forward part thereof and an adjustable stirrup set forwardly of the ball of the foot the ends having con- 95 nection with said toe-piece, the pressure of the foot upon said stirrup being adapted to hold the lower edge of the legging and toe-

piece on a line horizontal with the bottom of the sole of the boot or shoe, substantially as described and shown.

2. A legging adapted to cover the lower part 5 of the limb and the entire top of the shoe and the edge of its sole, a pliable strip fastened within the bottom of the legging and adapted to fit closely against the lower part of the top of the forward part of the shoe and the edge 10 of its sole, an adjustable stirrup attached to said strip forward of the ball of the foot and the strap forward of the heel to assist the

stirrup in retaining the legging down in a position on a line horizontal with the bottom of the sole around the entire shoe, substantially 15 as set forth and shown.

In testimony whereof we affix our signatures in presence of two witnesses.

WILLIAM S. CALLERY.
ROY SETTLE.
